UNITED STATES PATENT OFFICE.

AMES VAN WART, OF NEW YORK, N. Y.

DESIGN FOR A GROUP OF STATUARY.

Specification forming part of Design No. 5,089, dated July 4, 1871.

To all whom it may concern:

Be it known that I, AMES VAN WART, of the city, county, and State of New York, have invented a new and Improved Design for a Group of Statuary; and I do hereby declare that the following is a full, clear, and exact description thereof, which will enable others skilled in the art to make and use the same, reference being had to the accompanying photographs forming part of this specification.

The nature of my design, which is entitled

“The Arab Spahis,” is fully represented in the accompanying photographic illustrations, to which reference is made.

I claim as my invention—

The design for a group of statuary, as shown.

The above specification of my invention signed by me this 5th day of June, 1871.

AMES VAN WART.
